(57) **CLAIM**

The ornamental design for the awareness ribbon novelty lamp, as shown and described.

DESCRIPTION

FIG. 1 is a front top perspective view of the awareness ribbon novelty lamp.

FIG. 2 is a rear top perspective view of the awareness ribbon novelty lamp.

FIG. 3 is a front elevational view of the awareness ribbon novelty lamp.

FIG. 4 is a rear elevational view of the awareness ribbon novelty lamp.

FIG. 5 is a first lateral elevational view of the awareness ribbon novelty lamp.

FIG. 6 is a second lateral elevational view of the awareness ribbon novelty lamp.

FIG. 7 is a top plan view of the awareness ribbon novelty lamp.

FIG. 8 is a bottom plan view of the awareness ribbon novelty lamp; and,

FIG. 9 shows a series of three views of the awareness ribbon novelty lamp shown in a condition of use, namely, from left to right, the front elevational view, the first lateral elevational view, and the rear elevational view.

The broken lines showing an earthen support surface in FIG. 9 represent the environment and form no part of the claimed design. All other broken lines in the drawing views are included for the purpose of illustrating portions of the awareness ribbon novelty lamp that form no part of the claimed design.
